(57) **CLAIM**

The ornamental design for a toy, as shown and described.

DESCRIPTION

FIG. 1 is a perspective view of a toy showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof; and

FIG. 7 is a right side elevational view thereof.

FIG. 8 is a second embodiment perspective view of a toy showing our new design;

FIG. 9 is a front elevational view thereof;

FIG. 10 is a top plan view thereof;

FIG. 11 is right side elevational view thereof; and

FIG. 12 is a left side elevational view thereof. The rest of views thereof is the same as those of the embodiment of FIG. 1.

FIG. 13 is a third embodiment perspective view of a toy showing our new design;

FIG. 14 is a front elevational view thereof;

FIG. 15 is a top plan view thereof;

FIG. 16 is right side elevational view thereof; and

FIG. 17 is a left side elevational view thereof. The rest of views thereof is the same as those of the embodiment of FIG. 1.

FIG. 18 is a fourth embodiment perspective view of a toy showing our new design;

FIG. 19 is a front elevational view thereof;

FIG. 20 is a top plan view thereof;

FIG. 21 is right side elevational view thereof; and

FIG. 22 is a left side elevational view thereof. The rest of views thereof is the same as those of the embodiments of FIG. 1.

FIG. 23 is a fifth embodiment perspective view of a toy showing our new design;

FIG. 24 is a front elevational view thereof;

FIG. 25 is a top plan view thereof;

FIG. 26 is right side elevational view thereof; and

FIG. 27 is a left side elevational view thereof. The rest of views thereof is the same as those of the embodiments of FIG. 1.

FIG. 28 is a sixth embodiment perspective view of a toy showing our new design;

FIG. 29 is a front elevational view thereof;

FIG. 30 is a top plan view thereof;

FIG. 31 is right side elevational view thereof; and

FIG. 32 is a left side elevational view thereof. The rest of views thereof is the same as those of the embodiments of FIG. 1.

FIG. 33 is a seventh embodiment perspective view of a toy showing our new design;

FIG. 34 is a front elevational view thereof;

FIG. 35 is a top plan view thereof;

FIG. 36 is right side elevational view thereof; and

FIG. 37 is a left side elevational view thereof. The rest of views thereof is the same as those of the embodiments of FIG. 1.

FIG. 38 is an eighth embodiment perspective view of a toy showing our new design;

FIG. 39 is a front elevational view thereof;

FIG. 40 is a top plan view thereof;

FIG. 41 is right side elevational view thereof; and

FIG. 42 is a left side elevational view thereof. The rest of views thereof is the same as those of the embodiments of FIG. 1.

FIG. 43 is a ninth embodiment perspective view of a toy showing our new design;

FIG. 44 is a front elevational view thereof;

FIG. 45 is a top plan view thereof;

FIG. 46 is right side elevational view thereof; and
FIG. 47 is a left side elevational view thereof. The rest of views thereof is the same as those of the embodiments of FIG. 1.

FIG. 48 is a tenth embodiment perspective view of a toy showing our new design;

FIG. 49 is a front elevational view thereof;

FIG. 50 is a top plan view thereof;

FIG. 51 is right side elevational view thereof; and

FIG. 52 is a left side elevational view thereof. The rest of views thereof is the same as those of the embodiments of FIG. 1.

FIG. 53 is an eleventh embodiment perspective view of a toy showing our new design;

FIG. 54 is a front elevational view thereof;

FIG. 55 is a top plan view thereof;

FIG. 56 is right side elevational view thereof; and

FIG. 57 is a left side elevational view thereof. The rest of views thereof is the same as those of the embodiments of FIG. 1.

FIG. 58 is a twelfth embodiment perspective view of a toy showing our new design;

FIG. 59 is a front elevational view thereof;

FIG. 60 is a top plan view thereof;

FIG. 61 is right side elevational view thereof; and,

FIG. 62 is a left side elevational view thereof. The rest of views thereof is the same as those of the embodiments of FIG. 1.
